UNITED STATES PATENT OFFICE.

ROBERT D. THOMPSON AND JOHN PENROD, OF OKMULGEE, OKLAHOMA.

OIL-WELL EQUIPMENT.

Application filed October 28, 1922. Serial No. 597,590.

To all whom it may concern:

Be it known that we, ROBERT D. THOMPSON and JOHN PENROD, citizens of the United States, and residents of Okmulgee, in the 5 county of Okmulgee and State of Oklahoma, have invented certain new and useful Improvements in Oil-Well Equipments, of which the following is a specification.

This invention relates to oil well equipment and more particularly to a pump therefor.

Briefly stated an important object of this invention is to prevent the sand in the oil from lodging between the plunger and the 15 working barrel so that the working fit between the plunger and the working barrel will not be interfered with by the sand.

Further the invention forming the subject matter of this application aims to provide 20 simple means whereby the improved pump may be withdrawn from the well without being injured or mutilated.

A further object is to provide a pump of the character specified which is of highly 25 simplified construction, durable in use and cheap to manufacture.

Other objects and advantages of the invention will be apparent during the course of the following description.

30 In the accompanying drawing, forming a part of this application, wherein like numerals are employed to designate like parts throughout the same,

Figure 1 is a vertical sectional view 35 through a well pump constructed in accordance with this invention,

Figure 2 is an enlarged detail sectional view through the same,

Figure 3 is a horizontal sectional view 40 taken on line 3—3 of Figure 2,

Figure 4 is a side elevation of a guide member embodied in the invention, the said guide member acting to prevent the sand excluding sleeve from being mutilated during the removal of the pump from the well.

Figure 5 is a detail sectional view through the pump, the view illustrating the position the pump plunger assumes during its removal from the well.

50 In the drawings wherein for the purpose of illustration is shown a preferred embodiment of the invention the numeral 5 designates a working barrel secured to the lower portion of a tubing 6 through the medium of a coupling 7 and a sucker rod 8 is arranged within the tubing for recip-

rocating a plunger 9. As illustrated in Figure 1 the lower portion of the plunger 9 is provided with the usual valve 11 which is seated on the upward movement of the 60 plunger and which is opened on the downward movement of the same whereby the oil is then elevated on the upward stroke of the plunger rod, all of which is old and well known.

65 The plunger may be used with or without the cup valve 12 and in case of sandy formations the cup valve 12 may be omitted.

70 Figure 1 also illustrates that the lower portion of the working barrel 5 may be provided with the usual standing valve 14 which allows the oil to enter the working barrel but which prevents the escape of the oil through the lower end of the working barrel.

75 The improvement forming the subject matter of this application resides in a working sleeve or traveling sleeve 16 snugly fitted on the plunger 9 and having its lower portion interiorly screw threaded for threaded engagement with the lower portion of the plunger as indicated at 17.

80 As illustrated in Figure 2 the lower portion of the sleeve 16 is exteriorly reduced as indicated at 20 to form a wrench engaging surface. Any burrs left on the reduced portion 20 as the result of the use of a wrench on the sleeve will not interfere with the free movement of the sleeve 16 in the working barrel or loosen the working fit 85 which is ground between the parts.

85 On the downward stroke of the plunger 9 oil is introduced into the plunger and the oil passes out through a plurality of oil discharge slots 23 in the upper portion of 90 the plunger.

95 It will be observed that the upper end of the sleeve 16 is beveled as indicated at 24 to define a sharp edge which scrapes along the interior of the working barrel and prevents 100 sand from settling.

105 When the pump is not in operation, the sand in the oil above the pump settles and to avoid the settlement of sand between the working barrel and the plunger we have provided a beveled edge 24. The beveled edge 24 directs the sand back into the plunger and when the plunger subsequently begins to operate the oil picks up the sand and carries it out through the tubing in the usual 110 manner.

110 It will be observed that the beveled edge

not only maintains the working barrel free of sand as the result of scraping the barrel but also prevents the sand from settling between the barrel and the plunger. The bore 5 of the sleeve 15 is slightly enlarged at its upper portion and this enlarged bore forms a shoulder which terminates at the lower end of the slots 23 so that sand is prevented from dropping below the openings 23.

- 10 When it is desired to withdraw the pump from the well an upward movement is exerted on the sucker rod and the sharpened upper end of the sleeve 16 is engaged with a guide rod 26 which is loosely mounted on 15 the upper end of the working barrel 5. The upper end of the guide member 26 is slightly rounded as indicated at 30 so that it will freely pass the several joints encountered during the withdrawal of the pump. Figure 20 1 illustrates that the upper portion of the plunger is extended beyond the sleeve 16 and the extended portion of the plunger is snugly received within the tubular guide 26 during the removal of the plunger from 25 the well.

As the lower portion of the guide member 26 is exteriorly reduced in diameter it will be snugly received in the upper portion 24 of the barrel 16 so that the barrel will be held 30 against extensive lateral movement. That is to say the guide member 26 will contact with the side of the tubing and thereby limit the lateral movement of the barrel 16. Furthermore as the sharpened upper end 24 of the 35 barrel 16 is engaged with the lower portion of the member 26 the said sharpened end cannot flatly engage the several pipe ends encountered during the withdrawal of the working barrel from the well.

- 40 Attention is directed to the fact that the sand above the tubular guide 26 may pass between the guide and the lower piece of tubing 6 and the lower portion of the guide 26 is scalloped for the return or settlement 45 of the sand, the said scalloped portion being designated by the numeral 27.

In operation the pump 9 is operated in the usual manner and the oil passes out through the slots 23 of which there may be 50 any desired number. On each stroke of the pump the beveled edge 24 scrapes the interior of the barrel 5 and thereby maintains the same free of sand. In this manner sand is positively prevented from lodging between the sleeve 16 and the interior of the barrel.

When the pump is stopped the sand set-

ties and the beveled upper edge 24 directs the sand through the openings 23. When the pump is subsequently operated the sand which has been directed into the plunger will be forced out by the oil.

With reference to the foregoing description taken in connection with the accompanying drawings, it will be seen that the improved pump will not have to be pulled frequently to replace those parts which have rapidly worn as the result of the presence of sand. Consequently the production of oil is facilitated and the life of the parts is greatly prolonged.

In carrying out the invention the sleeve or liner 16 is preferably of a metal softer than the metal of the barrel 5, so that any wear which occurs will be almost entirely 75 on the liner. Thus, when it is desired to repair the pump in case of wear it is only necessary to replace the sleeve 16 by a new one as the wear is almost entirely on the liner.

Having thus described the invention, what is claimed is:—

1. The combination of a plunger provided adjacent its upper end with oil passages, and a sleeve connected to the plunger and terminating adjacent said oil passages, the upper end of said sleeve being provided with a combined sand scraper and sand guide, by means of which sand upon settling is directed into the plunger, 90 the bore of said sleeve being enlarged adjacent the top of the sleeve whereby to form a shoulder located at the lower end of said passages, and means whereby to protect and guide the sleeve during its withdrawal from 95 a well.

2. A pump for wells comprising a plunger, a sleeve mounted on the plunger and terminating below the top of the same, and a tubular guide arranged in the path of travel 100 of said sleeve and constituting a protecting means for the upper end of the same, the upper end of the sleeve being formed with a beveled edge adapted to scrape the interior 105 of the working barrel.

3. The construction set forth in claim 2, the upper end of said plunger being adapted to be received within said tubular guide.

4. The construction set forth in claim 2, said tubular guide having its lower end 110 formed with scallops for the passage of sand.

ROBERT D. THOMPSON.
JOHN PENROD.
